UNITED STATES PATENT OFFICE

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK

HIGH-FREQUENCY SIGNALING

Application filed September 22, 1916. Serial No. 121,571.

This invention relates to high frequency signaling, and more particularly to the relaying of messages, and has for an object to prevent a local circulation of power, or "singing", at a relaying station.

The invention provides for receiving a modulated wave having a certain carrier frequency, and in combining this modulated wave with locally generated oscillations to change the carrier frequency. Since the carrier frequency has been changed to a value to which the local receiving system is not receptive, the new carrier wave will be sent to the distant station and will not be received by the local receiving system.

The invention also provides for successively repeating a message by using a plurality of such repeating stations and by changing to a different frequency at each repeating station.

This will be better understood by considering the composition of a modulated carrier wave. If high frequency carrier oscillations are modulated or caused to vary in amplitude in accordance with the wave form of low frequency signal oscillations, the modulated carrier wave of varying amplitude is not a simple sine wave, but is complex in form. This modulated carrier wave may, however, be resolved into an unmodulated component or a carrier wave of constant amplitude and a modulated component comprising two waves whose frequencies are the sum and difference respectively of the carrier and signal frequencies.

If P is the carrier frequency and α the signal frequency, and if the carrier frequency has been modulated in accordance with the form of the signal wave, the modulated carrier wave may be resolved into three simple sine waves whose frequencies are P , $P-\alpha$, $P+\alpha$. It is to be understood that α represents either a single frequency useful in telegraphic signaling or the instantaneous frequency value of a modulating speech wave used in telephone signaling.

A demonstration that a modulated carrier wave may be so resolved is contained in the patent to Arnold 1,449,372, granted March 27, 1923, on application Serial No. 64,502, filed December 1, 1915.

According to this invention a modulated wave having a carrier frequency P is received at a repeating station. This is combined with locally generated oscillations of the high frequency q to produce sum and difference frequencies in a manner similar to the method of modulation explained above. Thus the side frequency $P+\alpha$ combines with the frequency q to produce the frequencies $q+P+\alpha$ and $q-P-\alpha$, and the side frequency $P-\alpha$ similarly gives the frequencies $q+P-\alpha$ and $q-P+\alpha$. Thus it is possible to repeat a modulated high frequency component at a frequency different from that at which it is received by combining other carrier oscillations therewith in a manner similar to the method of modulating a carrier wave in accordance with the signal wave. If it is desired to repeat at an increased carrier frequency, the circuit is tuned to transmit oscillations of frequency $(q+P)\pm\alpha$. The double sign ($\pm$) as used in this specification is to be read in the ordinary disjunctive sense, that is, "plus or minus". It may, however, in general, unless the context indicates otherwise, be read in the concomitant sense, that is, "plus and minus" it being stated hereinafter that either one or both side frequencies of a modulated wave may be raised or lowered in frequency in accordance with the present invention. Inasmuch as the unmodulated carrier component may or may not be suppressed or may be partly suppressed as hereinafter stated, it will be understood that energy of the unmodulated carrier frequency may or may not be present when both side bands are transmitted. For instance, if a modulated component of carrier frequency 50,000 is utilized to modulate carrier oscillations of 10,000, there is available for transmission a modulated component of carrier oscillations of frequency 60,000. Of course, the carrier frequency may be doubled by making $q=P$.

The modulated component received at a receiving station may be amplified and detected by combining it with locally generated oscillations of the carrier frequency according to the homodyne method disclosed in U. S. patent to Carson 1,449,382 granted March 27, 1923.

1923, on application Serial No. 64,524 filed December 1, 1915.

If it is desired to repeat the modulated component of the carrier oscillations at a frequency lower than that at which they are received, the sending circuit may be tuned to transmit the modulated component of frequency $(q-P) \pm a$. For instance, if the modulated component of carrier frequency 60,000 were received, this might be combined with carrier oscillations of frequency 20,000 in which case a modulated component of carrier oscillations of frequency 40,000 may be selected by a tuned circuit and transmitted.

These two steps, or any combination of them, for increasing and lowering the carrier frequency, may be used in conjunction for the successive repetition of signals, or the carrier frequency may be changed but once, as desired.

It will be apparent that after any side frequency which may be represented by $P+a$ or $P-a$ has been transmitted that the amplitude of these oscillations will be very small by the time they have reached a distant receiving station. One or both of these side frequencies however, is combined with carrier oscillations of frequency q , the amplitude of which may be very large in comparison to the feeble oscillations received. This results in new side frequencies, each having as components the components of the original unmodulated wave, that is, side frequencies equal to the sum and difference respectively of the incoming oscillations and the locally produced carrier oscillations. Accordingly, the upper side frequency $(P+q) \pm a$ produced by the combination of the local oscillations of frequency q with the incoming wave and also the lower side frequency $(P-q) \pm a$ have amplitudes which are large in comparison to the amplitude of the received oscillations, so that this scheme of modulation serves not only to change the carrier frequency, but also to increase the energy of the modulated component. Therefore there may be transmitted from the combining device a modulated component which has more energy than the one received. Such a side frequency wave may be used at any place where it exists to reproduce the signal represented by the original modulating wave in the manner specified in Carson Patent 1,449,382 mentioned above.

Further amplification may be secured by using amplifiers.

For a detailed description of a system which provides a method and means for practicing this invention, reference may be made to the drawings in which Fig. 1 shows diagrammatically the circuit arrangement for using the scheme of modulation at a repeating station; Fig. 2 indicates a plurality of repeating stations between the sending and receiving stations; Fig. 3 is a circuit diagram

of a repeating and monitoring station which serves to double the frequency of a carrier wave; Figs. 4 and 5 are forms of receiver circuits which may be used for detecting and indicating the signal modulated waves at a receiving station, such as the station Z; and Fig. 6 illustrates the application of the invention to a wire line system for repeating, amplifying and changing the frequency of carrier waves any desired number of times in transit between the signal initiating station W and the final receiving station Z.

In Fig. 1 the antenna 1 is tuned to receive either the side frequency $P+a$ or the side frequency $P-a$ transmitted from a distant station at which the remaining side frequency and the unmodulated carrier frequency P may or may not have been suppressed, as desired. As stated in Carson Patent 1,449,372 above referred to, better quality of received signals and more economical use of power at the transmitting station may be secured by transmitting only a single side frequency, for example, $P+a$. However, both side bands either with or without the unmodulated carrier component may be transmitted in accordance with the present invention with excellent results. As explained in Carson Patent 1,449,372, suppression of the unmodulated component makes it desirable, but not essential, that an unmodulated component be introduced and combined with the modulated component before detection. The antenna 1 and the local generator 2 of oscillations of frequency q are inductively connected to the input circuit of modulator 3, by means of the transformers 4 and 40, respectively. The modulator 3 is a three-element vacuum tube of the audion type, and comprises an evacuated vessel which encloses the cathode filament 5, grid 6 and anode or electrode 7. The grid potential is maintained negative by battery 8, and battery 9 heats the filament. The input circuit of the modulator is suitably tuned by variable condenser 10. The modulator space current is supplied by battery 11 through impedance coil 12.

As is characteristic of all vacuum tubes of the audion type, so is it true of the modulator 3, that the relation between the input voltage and the output current is non-linear, or successive small increments of voltage applied to the input circuit do not produce proportional increments in the output current. Accordingly, the tube is a distorting device and may be said to have a curved characteristic. Such a characteristic is essential in order that the sum and difference frequencies may be obtained.

If, in the sending, the suppression of the unmodulated component has been incomplete, beats of signal frequency a will be present in the modulator output circuit. This serves as a convenient means of ob-

serving the signal by detecting and indicating it in transit without the use of any local source or detecting apparatus other than that necessarily used in the repeater. Thus the transmission may be observed by receiver 13 connected to the modulator output circuit through transformer 14. The inductance 15 serves to keep the high frequency oscillations out of the receiver circuit. Condenser 16 shuts out the low frequency oscillations from the modulator output circuit which is inductively connected through transformer 17 to the input circuit of amplifier 18 of the audion type. For a detailed description of the operation of the audion type amplifier, reference may be made to Arnold Patent 1,129,942, March 2, 1915. The amplifier 18 is a three-element vacuum tube similar in structure to the modulator. The amplifier input circuit is tuned by variable condenser 19 and the output circuit is inductively connected to the input circuit of another amplifier 21 similar to amplifier 18, by transformer 20. The space current in the amplifier output circuits is supplied by batteries 22 and 23. The input circuit of amplifier 21 may be tuned by variable condenser 24, and its output circuit is inductively related to sending antenna 25 by means of transformer 26.

It is evident that a side frequency $P \pm a$ is received by antenna 1 and combined with locally generated oscillations of frequency q supplied by generator 2; the side frequency $(P \pm q) \pm a$ may then be selected by the tuned circuits, amplified, and transmitted from antenna 25. Since the sending antenna transmits carrier oscillations of a frequency different from the frequency for which antenna 1 is tuned, the outgoing energy will not affect the local receiving apparatus.

In Fig. 2 it is shown how the carrier frequency may be increased at one repeating station and subsequently lowered at another repeating station. In this figure, W represents a sending station, Z a receiving station, and X and Y intermediate repeating stations. The circuit arrangement at stations X and Y is substantially the same as that shown in Fig. 1, the only difference being in the tuning of the circuits and the frequency of the generators. As to Figs. 1 and 2, it is obvious that the location of the modulator and one of the amplifiers may be interchanged so that the signals may be amplified before they are modulated. It may be desirable to amplify first to intensify the effect in the monitoring circuit.

In Fig. 2, antennæ 1¹, 1² and 25¹, 25², correspond respectively to receiving antenna 1 and sending antenna 25 of Fig. 1. Also the generators 2¹ and 2² at stations X and Y respectively correspond to generator 2, Fig. 1. At stations X and Y the connections of the modulator and amplifiers are the same

as in Fig. 1, as indicated by the lines A—A, B—B, C—C, D—D, E—E, F—F.

At station W there is supplied a modulated wave which is transmitted and received by antenna 1 at repeating station X. Here the side frequency $P \pm a$ is combined with carrier oscillations of frequency q , delivered by generator 2¹. If it is desired to increase the carrier frequency, the side frequency $(P \pm q) \pm a$ is selected by the tuned circuits, 70 amplified and transmitted from sending antenna 25¹. If it is then desired to lower the carrier frequency, the side frequency $(P + q) \pm a$ is combined with carrier oscillations of frequency r , furnished by generator 80 2² at station Y, and the side frequency $(P + q - r) \pm a$ is selected by the tuned circuits, amplified and transmitted. The last mentioned side frequency may then be received at station Z and detected as indicated 85 above or in any suitable manner.

If, by way of example, $P = 40,000$, $q = 30,000$ and $r = 15,000$, then

X receives a frequency $40,000 \pm a$ and sends 90 a frequency $70,000 \pm a$.

Y receives a frequency $70,000 \pm a$ and sends a frequency $55,000 \pm a$.

So that X sends at a frequency different from that at which X receives and Y sends at a frequency different from that received by both X and Y. This prevents a local circulation of power and thereby prevents "singing".

Fig. 3 is a circuit diagram of a repeater station at which the carrier frequency is to be doubled. The apparatus of this station consists of the same elements as the elements of Fig. 1 combined in the same manner. The incoming high frequency energy may comprise components of frequency P , $P - a$, $P + a$ 100 or the unmodulated carrier frequency component P may be suppressed. But if desired the carrier and one side frequency may be suppressed. Local source 2 has the frequency of the incoming carrier that is $f = P$. The 110 outgoing wave will consist of the components of the modulated wave which are received with the carrier doubled that is, $2P$, as indicated on the drawing. In this arrangement, owing to the fact that the local carrier frequency is the same as the incoming carrier P and preferably of large amplitude, the signal reproduced in the receiver 13 will be of excellent quality, whether the unmodulated carrier component has been wholly or partly suppressed at the transmitter or not. If it is found convenient to double the carrier frequency the repeater station of Fig. 3 may be employed wherever the arrangement of Fig. 1 is suitable. Incoming and outgoing lines 115 may be substituted for the antennæ 1 and 25 respectively, if the station 3 is used in a wire system instead of a radio system.

Fig. 4 is a diagram of a receiving circuit 120 which may be used to receive modulated 130

waves consisting of one side frequency alone or both side frequencies with or without an unmodulated component. The receiving antenna 31 is preferably tuned to the same frequency as the transmitting antenna at the station from which signals are to be received. In line wire systems the incoming line takes the place of the antenna 31. Oscillation circuit 32 is preferably tuned to the same frequency as the antenna 31. Connected across the condenser 33 of circuit 32 is the input circuit of amplifier 34 of the well known three-element vacuum tube type of which the output circuit 34 is loosely coupled to a second oscillation circuit 36 tuned to the same frequency as the circuit 32. Loosely coupled to circuit 36 is source 37 generating continuous undamped waves of the carrier frequency of the incoming wave. Across condenser 38 of circuit 36 is connected detector 39 of the three-element vacuum tube type to the output circuit 40 of which is connected a receiving device 41 such as a telephone receiver.

Fig. 5 is a receiving circuit similar to the circuit of Fig. 4 in which the amplifier 34 and the tuned circuit 32 are omitted. This receiving circuit and its mode of operation are otherwise identical with the correspondingly numbered parts of the arrangement of Fig. 4.

Fig. 6 diagrammatically illustrates a wired system in which the scheme of changing the carrier frequency by means of a local source is applied in amplifying and repeating circuits placed at suitable intervals along the line between the station W where the transmitting signals originate and a receiving station Z. In this system the repeating stations are connected by conductive circuits instead of radio links consisting of pairs of antennae, one of which radiates energy to be received by the other. The carrier wave may have its frequency stepped up or down or doubled at each station in the system or it may be changed in any of these ways at a particular station regardless of the change which has occurred at the preceding station. For example, carrier waves of 100,000 cycles modulated in accordance with speech which originate at the station W may be stepped down to 80,000 cycles by means of a local source 2^1 of 20,000 cycles at the station X. The 80,000 cycle waves may in turn be stepped down to 65,000 cycles by means of a local source 2^2 of 15,000 cycle frequency at the station Y. The 65,000 cycle waves may then be transferred over the line from the station Y to the station Z and there used to reproduce signals by means of any receiver circuit such as the circuits of Figs. 4 or 5. Monitoring apparatus such as is used in the arrangements of Figs. 1 and 3 may be used at each repeating station to listen to the signal and thereby observe the transmission.

It is obviously immaterial as to the manner in which the steps of increasing and lowering the frequency are combined, or the frequency may be only lowered or increased. Furthermore, it is apparent that this invention is not limited to wireless systems, and that the sending and receiving antennae may be replaced by the sending and receiving conductors of a wired system.

While a local source of high frequency oscillations for changing the carrier frequency at the repeating station has been disclosed, it is to be understood that the invention is not to be limited to this means, as it is obvious that the object of the invention may be accomplished by combining with the incoming carrier current, energy in any form which will bring about a desired change in carrier frequency.

Although this invention has been described as particularly applicable to signaling systems, it is obvious that it may equally well be applied to other radio or conductive selective systems.

What is claimed is:

1. The method of signal transmission which comprises combining modulated carrier oscillations with electrical energy of different characteristic and in selecting for transmission from the resulting oscillations modulated oscillations having a frequency differing from that of said carrier oscillations.

2. The method of signaling which comprises combining a modulated wave of frequency f_1 with a wave of the high frequency f_2 and in selecting from the resultant wave a component wave having a carrier frequency differing from f_1 by the value f_2 .

3. The method of relaying signals which consists in receiving a modulated wave, locally generating a high frequency wave, combining said waves, and in selecting from the combined waves and transmitting a modulated component wave having a carrier frequency differing from that of the received modulated wave.

4. In a high frequency telephone repeating system, a receiving conductor adapted to receive a modulated wave, a generator of oscillations, means for combining the received modulated wave and said oscillations so as to produce a resultant wave, and means for selecting for transmission from said resultant wave a modulated wave component having a carrier frequency differing from that of said received wave.

5. In a signaling system, a source of modulated oscillations of frequency f_1 , a source of unmodulated oscillations of frequency f_2 , a distorting device, means for supplying oscillations from both said sources to said distorting device, and means for selecting from the resulting distorted oscillations, modulated

oscillations, having a frequency differing from f_1 .

6. In a signaling system, a source of modulated oscillations of frequency f_1 , another source of oscillations of frequency f_2 , a distorting device, means for supplying oscillations from both of said sources to said distorting device, and means for transmitting from said distorting device modulated oscillations having a frequency differing from f_1 by the value f_2 .

7. A signaling system comprising a thermionic device having an input circuit and an output circuit, a source of modulated oscillations and a source of high frequency oscillations, means for supplying oscillations from both of said sources to said input circuit, and means for selectively transmitting from said output circuit modulated oscillations having a carrier frequency differing from that of the oscillations supplied by said first named source.

8. In a system for relaying signals, the combination of a thermionic device having an input circuit and an output circuit, a source of modulated oscillations and a source of high frequency oscillations, both of said sources being adapted to energize said input circuit, said output circuit constituting a source of modulated oscillations having a carrier frequency differing from the frequency of the modulated oscillations supplied to said input circuit, and means for selectively amplifying the modulated oscillations produced by said last named source.

9. A plurality of repeating stations each comprising a conductor adapted to receive a modulated wave, means for changing the frequency of the modulated wave received at each of said stations, and a conductor at each of said stations adapted to transmit the modulated wave of changed frequency.

10. A plurality of repeating stations each comprising a conductor adapted to receive a modulated wave, a generator of high frequency oscillations at each of said repeating stations, the frequency supplied by each of said generators being different from that supplied by the generators at adjacent stations, means for combining the generated high frequency oscillations at each of said stations with the received oscillations, each of said combining means having associated therewith a conductor adapted to transmit a modulated wave having a frequency differing from that of the received wave.

11. In a high frequency signaling system, the combination of a plurality of repeating stations adapted to successively repeat a message, each of said stations comprising a conductor adapted to receive modulated oscillations of a frequency different from that of the modulated oscillations received by the adjacent stations, means for changing the frequency of the received oscillations, and a

conductor at each of said stations adapted to transmit the modulated oscillations of the new frequency.

12. In a high frequency signaling system, the combination of a plurality of repeating stations adapted to successively repeat a message, each of said stations comprising a conductor adapted to receive modulated oscillations of a frequency different from that of the modulated oscillations received by the adjacent stations, a source of high frequency oscillations at each of said repeating stations, the frequency supplied by each of said sources being different from that supplied by the sources at adjacent stations, means for combining the generated oscillations at each of said stations with the received oscillations, each of said combining means having associated therewith a conductor adapted to transmit a modulated wave having a frequency differing from that of the oscillations received at its respective repeating station.

13. The method of producing a modulated carrier wave having no unmodulated component of the carrier frequency which comprises, producing a pure modulated wave and changing each of its instantaneous individual frequency components thereof by a constant amount to produce a resultant modulated wave of the desired carrier frequency.

14. The method of carrier transmission comprising modulating a carrier wave, selecting at least one component of the resulting energy, causing said selected energy to modulate a second carrier wave and selecting at least one component of said modulated second wave.

15. The method of carrier transmission comprising modulating a carrier wave, suppressing substantially all of the unmodulated component of the frequency of said carrier wave, causing the resulting energy to modulate a second carrier wave, and suppressing substantially all of the component of one of the combination frequencies of said carrier waves.

16. The method comprising combining two waves, selecting from the resulting energy a single component having a frequency differing from that of one of said waves by the frequency of the other, causing said component to vary the amplitude of a third wave, and transmitting energy proportional to that of said third wave.

17. The method comprising combining two waves, selecting from the resulting energy a single component having a frequency differing from that of one of said waves by the frequency of the other, causing said component to vary the amplitude of a third wave, transmitting energy proportional to that of said third wave, and detecting said transmitted energy.

18. The method of signaling comprising modulating a carrier wave, suppressing all

components except one side frequency component of the modulated carrier wave, and causing this unsuppressed component to modulate a second carrier wave.

19. The method comprising varying the amplitude of a substantially constant frequency wave in accordance with a signal or control wave, suppressing all components of the resulting energy except one side frequency component, combining said side frequency component with another wave of substantially fixed frequency, and transmitting the resulting energy to a receiving station.

20. In a carrier transmission system, a source of carrier oscillations, means for modulating said oscillations, means for selecting at least one of the resulting energy components to the exclusion of another resulting component, a carrier wave source, means for causing said selected energy to modulate a wave supplied by said carrier wave source, and means for selecting at least one component of said modulated carrier wave.

21. In a carrier transmission system, means for supplying a carrier wave, means for modulating said wave and for suppressing substantially all of the unmodulated component of the carrier frequency, means for supplying a second carrier wave and for modulating said second wave in accordance with the unsuppressed components resulting from the modulation of said first wave, and means for suppressing substantially all of the component of one of the combination frequencies of said two carrier waves.

22. In a carrier transmission system, means for supplying a carrier wave, means for modulating said wave and for suppressing substantially all of the unmodulated component of the carrier frequency, means for supplying a second carrier wave and for modulating said second wave in accordance with the unsuppressed components resulting from the modulation of said first wave, means for suppressing substantially all of the component of one of the combination frequencies of said two carrier waves, and means for transmitting the resulting energy to a distant station.

23. In combination, a combining device, means for impressing thereupon two waves of different frequencies, means for selecting from the resulting energy a single component having a frequency differing from that of one of said waves by the frequency of the other, means for supplying a third wave, means for causing said selected component to vary the amplitude of said third wave, and means for transmitting energy proportional to that of said third wave.

24. An electrical system comprising a carrier wave source, means for modulating the wave supplied by said source and for suppressing all of the components of the modu-

lated carrier wave except one side frequency component, a second carrier wave source, means for causing said unsuppressed component to modulate the wave supplied by said second source, and suppressing the unmodulated component.

25. A transmitting station, a distant receiving station, means at said transmitting station to transmit modulated waves, an intermediate repeating station having a local source of waves, a combining device, means for impressing the modulated wave received from said transmitting station and waves from said local source together upon said combining device, means connected to said combining device to transmit to said receiving station resultant modulated waves of different carrier frequency than said received waves, and a monitoring receiver connected to said combining device to indicate signals corresponding to the received modulated waves detected by said device.

26. The method of conveying signals transmitted by a high frequency wave comprising independently producing another high frequency wave, causing said waves to interact to produce a signal controlled wave of lower frequency than the transmitted wave, selectively receiving said signal controlled wave and acting upon said signal controlled wave to receive the signal component thereof.

27. In a high frequency signaling system, means for receiving high frequency waves, means for combining said waves with locally generated waves of high frequency to produce waves of frequency lower than said received waves but of inaudible frequency, means for amplifying said inaudible lower frequency waves, and means for deriving intelligible signals from said amplified waves.

28. In a radio system, means for receiving a signal modified radiant energy wave of a given high frequency, means for combining therewith locally generated oscillations to produce a similarly modified wave of lower but inaudible frequency, means for amplifying said lower frequency wave, and means for detecting said amplified wave.

29. The method of high frequency signaling which comprises receiving high frequency carrier waves, combining therewith locally generated waves of greater energy to produce beat frequency waves of higher than essential speech frequency, selecting said beat frequency waves, and combining therewith other waves to produce intelligible signal waves of audio frequency.

30. The method of radio signaling which comprises receiving carrier waves, combining therewith locally generated waves to produce inaudible beat frequency waves of greater energy than the received waves, selecting said inaudible waves, and combining

therewith other waves to produce intelligible signal waves.

31. An electric wave signaling system which comprises in tandem arrangement a plurality of groups of devices, each group constituting means for receiving a wave whose frequency components are above essential speech frequencies, means for changing the frequency components by a locally predetermined amount to produce another wave whose components consist of other frequencies above essential speech frequencies, and means for conveying the produced wave to a succeeding point in the system.

32. The method which comprises combining high frequency waves with other waves to produce high frequency waves of a third frequency and combining waves with the waves of said third frequency to produce high frequency waves of a frequency other than the waves of said third frequency or the waves combined therewith, each of said produced waves having a frequency above essential speech frequencies.

33. A radio signaling system which comprises means for receiving radiated carrier waves, means for combining therewith locally generated waves to produce inaudible beat frequency waves, means for selecting said inaudible waves, and means for combining therewith other waves to produce intelligible signal waves.

34. The method of transmitting a modulated band of frequencies corresponding to one side band resulting from modulation to the exclusion of the unmodulated carrier frequency and other side band components which consists in modulating in accordance with the signals to be transmitted a wave of frequency lower than said carrier frequency, selecting one of the side bands of said modulated wave to the exclusion of the other side band and the unmodulated component, and modulating a wave of said carrier frequency in accordance with said selected band.

35. The method of transmitting a modulated band of frequencies corresponding to one side band resulting from modulation to the exclusion of the unmodulated carrier frequency and other side band components which consists in modulating in accordance with the signals to be transmitted a wave of frequency lower than said carrier frequency, selecting one of the side bands of said modulated wave to the exclusion of the other side band and the unmodulated component, modulating a wave of said carrier frequency in accordance with said selected side band, and selecting one side band of said modulated carrier frequency wave.

36. A carrier wave transmission system for producing a modulated band of frequencies corresponding to one side band resulting from modulation to the exclusion of the unmodulated carrier frequency and other side

band components, comprising means for modulating in accordance with signals to be transmitted a wave of frequency lower than said carrier frequency, means for selecting one of the side bands of said modulated wave to the exclusion of the other side band and the unmodulated component, and means for modulating a wave of said carrier frequency in accordance with said selected side band.

37. A radio transmitting system comprising a plurality of repeater stations in tandem arrangement and means at each of said stations for transferring the signal from the received carrier wave to a carrier wave of lower frequency, said means comprising a wave distorting device, a local source of high frequency current, and means for impressing the received carrier wave and the locally generated current simultaneously upon said distorting device.

38. A radio transmitting system comprising a plurality of repeater stations in tandem arrangement and means at each of said stations for transferring the signal from the received carrier wave to a carrier wave of higher frequency, and means comprising a wave distorting device, a local source of high frequency current, and means for impressing the received carrier wave and the locally generated current simultaneously upon said distorting device.

39. A radio station for receiving and re-radiating energy comprising a local source of high frequency waves, a wave distorting device at said station, and means for simultaneously impressing on said wave distorting device waves from said high frequency source and carrier waves received at said repeater station, and means for impressing the resultant waves on a radiating conductor.

40. The method of indirectly amplifying high frequency electrical oscillatory energy which comprises combining said energy with high frequency continuous electrical oscillations of a frequency differing from said energy by a third readily-amplifiable high frequency, converting the combined energy by suitable means to produce said readily-amplifiable high frequency oscillations and amplifying said resulting readily-amplifiable high frequency oscillations.

41. The method of preventing the generation of undesired oscillations in a high frequency wave amplifying system which comprises impressing high frequency waves to be amplified on the input circuit of the system, converting the waves during amplification from one high frequency directly to another high frequency, and thereby producing in the output circuit amplified high frequency waves of a frequency different from the frequency applied to the input circuit and which the input circuit is not adjusted to receive efficiently.

42. The method of receiving high fre-

quency oscillations wherein the incoming energy is utilized to produce oscillations of a different locally predetermined frequency above good audibility which are then amplified and transmitted to a conductive wave transferring circuit.

43. The method of amplifying and utilizing in a signaling system high frequency signal modulated oscillations wherein the oscillations are utilized to produce oscillations of a different locally predetermined high frequency which are then amplified and the resultant amplified energy further utilized as a carrier wave in the signaling system.

44. The method of indicating carrier wave repeating in a system operating to convert the energy of the carrier wave from one carrier frequency to another by a thermionic frequency converting device which comprises producing indications by low frequency components in the output current from the converting device.

45. The method of impressing electrical energy representing a signal or message upon a transmitting medium, which consists in producing electric currents of different inaudible frequencies interacting to produce beats of inaudible frequency, controlling the energy to represent the signal or message to be transmitted, and impressing the beat energy upon the transmitting medium.

46. Transmitting apparatus comprising means for producing electric currents of different inaudible frequencies interacting to produce beats, means for controlling the energy to represent a signal or message, means for amplifying the beat energy, a transmitting medium, and means for impressing the amplified beat energy upon said transmitting medium.

47. Transmitting apparatus comprising means for producing electric currents of different inaudible frequencies interacting to produce beats, a transmitting medium, and a circuit intervening between said means and said transmitting medium for selectively discriminating in favor of and transferring to a frequency intermediate said beat producing frequencies.

48. The method of observing carrier wave repeating in a system operating to convert the energy of the carrier wave from one carrier frequency to another which consists in applying the carrier waves to a frequency converting device together with other waves to produce modulated carrier waves of a frequency different from the waves to be converted, and observing low frequency signaling components in a circuit coupled to the converting device.

49. The method of amplifying high frequency electrical oscillatory energy which comprises combining the high frequency energy to be amplified with other locally produced high frequency oscillations of a fre-

quency differing from the energy to be amplified by a third readily-amplifiable high frequency, converting the combined energy by suitable means to produce oscillations of said readily-amplifiable high frequency, selecting the energy of the third high frequency oscillations from other oscillations, and amplifying the selected oscillations.

50. The method of producing a desired carrier wave, modulated in accordance with voice currents, from a carrier wave of different frequency modulated in accordance with the same voice currents, which comprises producing a wave having a frequency equal to the difference of the frequencies of said waves and causing the last mentioned wave to interact with said wave of different frequency to produce the desired wave.

51. A repeating system comprising the combination of a high frequency line adapted to receive a carrier wave of frequency p modulated in accordance with signals from a distant station, a vacuum tube device adapted to be supplied by said line and having an input circuit and an output circuit, means for tuning said input circuit to a signal wave having the carrier frequency p , means for tuning said output circuit to a signal wave having the carrier frequency $2p$, and a high frequency line associated with said output circuit.

In witness whereof, I hereunto subscribe my name this 20th day of September, A. D. 1916.

BURTON W. KENDALL.
